(57) **CLAIM**

The ornamental design for a buckle as shown and described.

DESCRIPTION

FIG. 1 is a front, left-side top, perspective view of a buckle, showing the new design;

FIG. 2 is a front elevational view thereof;

FIG. 3 is a rear elevational view thereof;

FIG. 4 is a left-side elevational view thereof;

FIG. 5 is a right-side elevational view thereof; and,

FIG. 6 is a top plan view thereof, the bottom plan view (not provided) being a mirror image of the top plan view.

The broken lines depict parts of the buckle that form no part of the claimed design.

1 Claim, 5 Drawing Sheets
